UNITED STATES PATENT OFFICE.

JAMES FLYNN, OF SOO JUNCTION, MICHIGAN.

SHEET-MUSIC MOVING AND TIME-KEEPING APPARATUS.

1,352,363.

Specification of Letters Patent. Patented Sept. 7, 1920.

Application filed September 13, 1919. Serial No. 323,518.

To all whom it may concern:

Be it known that I, JAMES FLYNN, a citizen of the United States, residing at Soo Junction, in the county of Luce and State of Michigan, have invented new and useful Improvements in Sheet-Music Moving and Time-Keeping Apparatus, of which the following is a specification.

One of the objects of my present invention is the provision of an apparatus for moving a sheet or web of music rectilinearly before the eye of the player of an instrument, thereby obviating the necessity of turning sheets of music as is necessary under the ordinary well known arrangement at present in vogue.

Another object of the invention is the provision in combination with the rectilinearly movable sheet and means for moving such sheet at various speeds as desired by the operator in combination with a fixed pointer which guides the eye of the player to the chord to be played, and at the same time enables the player to observe strict time.

Another object of the invention is the provision in combination with the rectilinearly movable sheet or web of music of automatically movable line-indicating means.

Other objects and practical advantages of the invention will be fully understood from the following description and claims when the same are read in connection with the drawings, accompanying and forming part of this specification, in which:

Figure 1 is a front elevation of the apparatus constituting the best practical embodiment of my invention that I have as yet devised.

Fig. 2 is a top plan of the same.

Fig. 3 is an elevation of the left-hand end of the apparatus.

Fig. 4 is an elevation of the right-hand end thereof.

Fig. 5 is a transverse section taken in a plane at the right of the pointer 11 in Fig. 1, looking toward the left.

Fig. 6 is an inverted plan view of the apparatus illustrating the arrangement of the motor in the base and the connection of the said motor with the parts that derive motion therefrom.

Fig. 7 is an enlarged detail view illustrative of the mechanism for feeding the line indicator downwardly and bringing about the automatic release of said indicator at the completion of the downward movement

thereof and the subsequent quick raising of the indicator.

Fig. 8 is a transverse section taken in the plane indicated by the line 8—8 of Fig. 7. 60

Fig. 9 is a section on line 9—9 of Fig. 8.

Similar numerals of reference designate corresponding parts in all the views of the drawings:

My novel apparatus comprises among 65 other elements a base 1. In the said base 1 is arranged a motor 2, preferably, though not necessarily, of spring type. The motor *per se* is provided with a winding crank 3, and is otherwise of the ordinary well known construction. 70

Disposed in upright position above the base 1 adjacent to one of the ends thereof is the idler roll 4 of the apparatus. This roll 4 is mounted at its lower end on the 75 base, so as to permit of the roll being swung to a slight extent laterally lengthwise of the base on a center of movement located adjacent to the upper side of the base.

Mounted in upright position adjacent to 80 the opposite end of the base is a power roll 5 through the medium of which the sheet of music is moved in the direction of its length as hereinafter described.

The rolls 4 and 5 are provided at their 85 upper ends with trunnions or shaft sections 6, and suitably connected to the upper end of the shaft section 6 of the roll 4 is a bar section 7. Connected at one end in hinged manner to the said bar section 7, and at its 90 opposite end in hinged manner to the shaft section 6 of the power roll 5, is a toggle lever 8. When said toggle lever 8 is in the position shown by full lines in Fig. 1, the idler roll 4 is maintained in the position illustrated in said figure, with a view to holding the sheet 9 under tension. When, however, the toggle lever 8 is flexed upwardly, as indicated by dotted lines in Fig. 1, the shaft section 6 may be readily withdrawn from the 95 idler roll 4 for the removal of the sheet 9 and the placing of a fresh sheet on the rolls 4 and 5.

It will be understood in this connection that the end of the toggle lever 8 adjacent to the power roll 5 is also detachable 100 from said power roll so as not to interfere with the removal of a sheet from the rolls and the mounting of a fresh sheet on the rolls. The motor is connected with the power roll 5 preferably in the manner shown 105 in Fig. 6, and so as to enable the motor to move the forward stretch of the sheet 9 from

right to left. The said sheet 9 is in the form of an endless web or belt, and is provided in its inner side adjacent to its lower edge with an elastic or friction-creating strip 10, designed to enable the power roll 5 to better feed the sheet. In the preferred embodiment of my invention, the music is written, printed or otherwise inscribed on the outer side of the sheet 9 in a spiral manner lengthwise of the sheet, and so that the music may be read continuously from the beginning to the end thereof.

10 Fixed to and rising from the base 1 in front of the forward stretch of the endless sheet 9 is a pointer 11 which indicates the playing point to be observed by the player.

15 Rising from the base 1 adjacent to one end thereof is an upright slotted guide post 12, and mounted adjacent to the opposite end of the base and extending upwardly therefrom is a threaded shaft 13 that is driven from the motor 2 through the driving connection shown in Fig. 6. Mounted on and engaging the shaft 13 is a nut 14 that is designed to be fed downwardly incidental to turning of the said shaft 13. Connected with and movable downwardly by the said nut 14 is a line-indicator 15, designed as its name imports to mark the line to be played, 20 with a view to assisting a student in reading the music. The free end portion of the said indicator 15 is movable vertically in and held against lateral deflection by the post 12.

25 In the practical operation of my improvement as thus far described, it will be observed that when the sheet 9 is properly mounted on the rolls 4 and 5 and placed under tension, and the motor 2 is started, the forward stretch of the sheet 9 will be fed from right to left. Manifestly the speed of such feed may be increased or diminished by regulation of the motor 2. It will also be noted that incidental to the described feed or movement of the sheet 9, the indicator 15 will be slowly moved downward so as to approximately designate the line that is to be followed, also that the pointer 11 will serve as a guide to assist the player in determining the notes that are to be played. The indicator 15 and the pointer 11 are designed more particularly for the use of students, and when the apparatus is to be used by a finished performer, the pointer 11 as well as the indicator 15 and the appurtenances of 30 the latter may be omitted without affecting my invention considered in the broader aspect thereof.

35 The nut 14 complementary to the screw or threaded shaft 13 is of the construction best shown in Figs. 7, 8 and 9, and is designed to coöperate with a cone 20 on the lower portion of the shaft 13, and with a cone 21 on the upper end of said shaft. This will be better understood when it is stated that at 40 the completion of its downward movement,

the nut 14 is disengaged by the cone 20 from the thread on the shaft 13, whereupon the nut 14 and the indicator 15 are quickly raised as a unit by a spring 22 to the uppermost point, where the nut 14 by coöperation with the upper cone 21 will be reengaged with the thread of the shaft 13 so as to bring about a subsequent downward feed of the nut 14 and indicator 15. This provision permits of the composition that is being played 45 being repeated without interrupting the operation of the apparatus.

50 It will be apparent from the foregoing that my novel apparatus obviates the necessity of the performer turning leaves or otherwise manipulating the music that is being played after the apparatus is once placed in operation.

55 As before indicated, the construction herein illustrated and described constitutes the best practical embodiment of my invention of which I am cognizant and have therefore described the said embodiment specifically in order to impart a full, clear and exact understanding of the same. I do not desire, 60 however, to be understood as confining myself to the specific construction and relative arrangement of parts, inasmuch as in the future practice of the invention, changes in the form and relative arrangement of the 65 elements may be made without involving departure from the scope of my invention as defined in my appended claims.

Having described my invention, what I claim and desire to secure by Letters-Patent, 70 is:

1. Apparatus for the purpose described, comprising a base, upright rolls mounted thereon, one of said rolls being movable laterally, means for transmitting rotary motion to one of said rolls, and a toggle lever connected with said rolls and adapted when flexed to permit inward movement of the laterally movable roll and when extended to move said roll outwardly and thereby place 75 a belt-like sheet on the rolls under tension.

2. In an apparatus to move an endless music sheet on which music is inscribed in a spiral manner lengthwise of the sheet, the combination of means to move the sheet 80 rectilinearly, and a line indicator connected with the sheet-moving means and arranged substantially parallel to the lines on the sheet and movable throughout its length by the sheet-moving means in a direction substantially at right-angles to the line of movement of the sheet and without affecting the substantial parallel relation of the indicator to the lines on the sheet.

3. Apparatus for the purpose described, 85 comprising a base, upright rolls mounted thereon, one of said rolls being a power roll and the other an idler roll, means for transmitting rotary motion to the power roll, shaft sections engaging and extending up- 90

wardly from the rolls, a bar section on one shaft section, and a toggle lever hinged at one end to one shaft section and similarly connected at its opposite ends to the bar section on the other shaft section.

- 5 4. In an apparatus to move an endless music sheet on which music is inscribed in a spiral manner lengthwise of the sheet, the combination of means to move the sheet
10 rectilinearly, a line indicator movable to a corresponding degree throughout its length in a direction at right angles to the line of movement of the sheet, and disposed at all times in approximate parallelism with the
15 lines on the sheet, and means to so move the line indicator at the same time that the sheet is moved.
5. In music moving apparatus, the combination of spaced rolls, means for transmitting
20 rotary motion to one roll adapted for the mounting thereon of a belt-like sheet

bearing music, a stationary pointer for co-operating with the said sheet, and a movable line indicator for also coöperating with the said shaft, said line indicator deriving motion from the same source of power as the power roll and being moved to the same degree throughout its length in approximate parallelism to music on the sheet.

6. Apparatus for the purpose described, 30 comprising means to move a music-bearing sheet rectilinearly, a line indicator, a screw shaft, cones adjacent to the opposite ends thereof, a nut movable on and by the shaft and carrying the line indicator and controlled by the said cones, and a spring for quickly moving the said nut in one direction after the same is engaged by one of the cones from the screw shaft.

In testimony whereof I affix my signature. 40

JAMES FLYNN.
